GAS MAIN STOPPER

Victor E. Ankario, Hammond, Ind.

Application May 2, 1941, Serial No. 391,583

4 Claims. (Cl. 138—94)

This invention has as its principal object the provision of improvements in gas main stoppers of the type including a diaphragm which is inserted into the pipe and expanded to block the main gas flow, and which is further provided with pneumatically expandable means inflated, when the stopper is in position, to provide a complete seal around the edges thereof, with the particular object of filling irregular spaces and rough casting formations existing on the interior of such pipes so that the seal is complete.

Another and more specific object is the provision of an improved expandable frame on which the flexible diaphragm of the stopper is mounted.

A further object is the provision of a combination coupling and handle mounting, the coupling including means for connection with a compressed air line or pump, and a pivoted handle element adapted to be manipulated in working the stopper into the main.

Still another object is the provision of roller means on the coupling and handle attachment for facilitating the manipulation of the stopper into position in the main.

Yet another object is the provision of an improved mounting for a pneumatic tube around the rim of an expandable frame, together with improved means for attaching an expandable diaphragm over the tube to said frame.

It is a further object of this invention to provide a novel arrangement of spring and rubber frame which will coact to produce a uniform expansion and a ridged body capable of withstanding the twist created by pipe pressure.

A still further object relates to the provision of a telescopic brace member on the expandable frame, a part of which brace member is adjustably mounted in the coupling member to provide an air connection between the pneumatic coupling means and the expandable tube on the frame structure, together with means for adjusting said telescopic member to clamp the tube into sealing engagement therewith.

Other objects, advantages and novel aspects of the invention reside in certain details of construction as well as the cooperative relationship of the component parts of the illustrative embodiment described hereinafter in view of the annexed drawing, in which:

Fig. 1 is a fragmentary section through a gas main showing my new stopper in operative position with respect thereto;

Fig. 2 is a vertical sectional detail, partly in elevation, as seen from line 2—2 in Fig. 1;

Fig. 3 is a vertical sectional detail of the head portion of the stopper as seen from line 3—3 in Fig. 2;

Fig. 4 is a vertical sectional detail through the lower portion of the stopper as seen from line 4—4 in Fig. 2;

Fig. 5 is a fragmentary perspective view illustrating the arrangement of the inflatable tube on the frame at the head portion of the stopper;

Fig. 6 is a fragmentary perspective view partly in section illustrating the arrangement at the lower portion of the stopper;

Fig. 7 is a horizontal sectional detail through the periphery of my new stopper; and

Fig. 8 is a force diagram concerning the new stopper.

Referring to the drawing, the stopper is adapted to be used in cutting off flowage through a pipe generally indicated at 10 (Fig. 1) having a small opening 11 cut in its top area so as to permit the introduction of the stopper into the pipe. The stopper is indicated at 12 and constitutes a frame structure 13 which is normally adapted to assume an oval shape as seen in Fig. 2 and is constructed such that it may be forced into a substantially circular shape in a manner later to be described.

The expandable frame 13 consists of a pair of spaced shackle members 14 generally channeled shaped and each of these shackles has extending therefrom at right angles to the oval, a tubular member 15. These tubular members are preferably square in cross-section and are so constructed as to be telescopically arranged with respect to each other, as seen in Fig. 2, to form a center strut member. The frame structure further consists of a pair of spring elements 16, each of which has its end portions pivotally connected as at 17 to an upper and lower shackle member 14. As will be noted in Fig. 2, the springs 16 are so characterized as to normally bias the frame structure 13 into a substantially oval shape.

Each of the spring members 16 are preferably the leaf type having a plurality of leaf spring elements graduating in length so as to strengthen the spring 16 in its mid-section. The individual leaves 46 of the spring 16 are normally clipped together by winding a wire element 45 about the assembly at certain intervals, each clip being welded to the main spring element 16' while permitting the other leaves to move freely. Each of the spring members 16 is encased within the rubber coating 18, which coating is molded around the spring proper while the rubber is in a plastic state. The spring element 16 having

first been brass plated so that the plastic rubber will adhere to the metallic spring to produce a relatively monolithic structure. The coating 18 extends the full length of the spring 16 and has one surface, the outside with respect to the frame, recessed or concaved as at 19 to provide a seat for a pneumatic tube 20 which is arranged around the periphery of the frame in a manner now to be described.

The inflatable tube 20 has one end portion thereof sealed up as at 21 and in assembling the tube 20 on the frame the sealed end 21 is inserted through an opening 22 formed in the upper strut element 15 and is passed up through the hollow member 15 through an opening in the web 14' of the upper shackle 14. The tube 20 is then arranged around the frame so that the sealed end portion 21 overlaps a portion of the tube 20 as illustrated in Fig. 5.

Each of the channels 14 is provided with a rubber filler 18' which is adapted to support the tube 20 in its relative position about the periphery of the stopper member.

A diaphragm 23 is then stretched upon the frame 13 and this diaphragm is preferably constructed of impervious material such as rubber. The diaphragm 23 is mounted upon the frame so as to span the area circumscribed by the peripheral edge thereof, and the edges of the diaphragm are folded around the pneumatic tube and spring assembly as well as the shackle arrangement, and the free edges of the diaphragm are vulcanized as at 24 to the inner face of the diaphragm. The edge portion of the diaphragm which surrounds the shackle elements 14 is anchored in place by a plate 25 having a screw connection as at 26 with one of the flanges of the channel 14 to assure a firm grip upon the diaphragm and to prevent tearing of the rubber element at an opening 27 provided therein where it fits around the strut 15 extending from the channel 14.

Another feature of the invention relates to the lever attachment for positioning the diaphragm within the pipe 10. This leverage comprises a long manipulating handle 28 which has its end portion pivotally arranged as at 29 in a trunnion 30 formed at the lower end of the lowermost strut 15. The trunnion 30 further providing a mounting as at 31 for a gliding means in the form of a roller 32. The other lever means is indicated at 33 as has its inner end portion pivotally connected as at 34 to the upper end of the uppermost strut member 15. This lever 33 is provided with a series of tooth formations 35 and extends from and forms an integral part of the hand pump 36.

In the operation of the device, the stopper is normally in the oval or collapsed position illustrated in Fig. 2 and after the hole 11 has been cut into the pipe 10, the stopper is inserted through the opening 11 with the handle and lever 28-33 pivoted into alignment with the long axis of the oval frame 13. The lever 33 is then arranged with one of the tooth formations 35 engaging the edge of the opening 11 so that the upper portion of the stopper 12 is adapted to engage the upper inner surface of the pipe 10, the pivotal connection 34 of the lever to the frame 13 forms a fulcrum and the lower end portion of the stopper is then pulled to the left through the medium of the handle 28 and the expansible frame is arranged in the vertical position shown in Fig. 1. The roller 32 relieving

any frictional engagement of the lower edge of the stopper with the inner surface of the pipe. When the stopper has been positioned as aforesaid, the tube 20 is inflated through the medium of the pump 36 which has connection with the freely extending section 20' of the pneumatic tube.

In connection with the inflating of the tube, there is arranged between the pump and the hose 20' a valve member 37 whereby air pressure is permitted to pass from the pump 36 into the pneumatic tube and is held within the tube by a valve 38, there being a release valve 39 associated with a by-pass 40 which assures against the pressure exceeding a maximum load and at the same time forms a release valve whereby the air may be released from the pneumatic tube when it is desired to deflate the latter.

As shown in the diagrammatic illustration, Fig. 8, the diaphragm 23 forms a wall which is acted upon by the pressure from within the gas main, which pressure is uniform in pounds per square inch over the entire circular area of the diaphragm. The inflated tube 20 causes the peripheral surface of the rubber diaphragm to engage the inner surface of the pipe 10 and to seat into the small sand mold depressions, usually found in the type of pipe used in gas mains, to prevent any leakage of the fluid within the pipe. It will be noted from the force diagram that by reason of the forces acting upon the diaphragm there is a tendency for the frame structure in and about the spring sections 16 to rotate in the direction of the arrows. It is to this end that the rubber coating formed about the springs 16 acts as a reinforcing agent which prevents a twisting of the springs 16 in their medial portion so that at all times there will be a definite engagement of the peripheral edge of the stopper against the inner wall of the pipe 10.

It will be noted that the wire elements 45 are fixed to but one of the leaf spring members 46 so as to bind the several leaf springs together and yet permit longitudinal movement of each spring leaf with respect to the main spring 16. By the same token it will be noted that the free ends of the wire elements are looped with the bight portion of these loops extending in a direction of the outer or recessed portion 19 of the rubber coating 18. By this arrangement the coating 18 when molded upon the springs 16-46 is bonded to the latter by the looped ends of the wire and the side flanges of the coating 18 embracing the concavity 19 are reinforced periodically to transmit any rotational torque in the direction of the arcuate arrows (Fig. 8), into the main spring members 16.

The rubber coating formed upon the springs 16 in addition to acting as a reinforcing agent for these springs also adds to the strength of the spring. That is to say, the spring has a tendency to return to a normal position against any outer force which acts to bias the spring. The resilient rubber coating 18 formed around the spring adds to this force which tends to return the spring to a normal position. These two forces acting together cause a spreading of the upper and lower edges of the stopper so that when the stopper is manipulated into the position shown in Fig. 1 by the handle and lever the spring will be biased into a circular form with the peripheral edges of the stopper bearing against the inner walls of the pipe even though the pneumatic tube 20 has not been inflated. Thus it is seen, that the spring members have

a normal bearing relationship on the inner walls of the pipe to maintain the diaphragm in its position and that by reason of the inflation of the pneumatic tube there is an added bearing force against the inner wall of the pipe which may be increased in proportion to the air pressure caused by the fluid within the pipe.

The various advantages and objects of the invention may be accomplished by modifications of the particular embodiment specifically described herein, and it is intended that the appended claims shall include all equivalent arrangements fairly coming within their call.

Having thus described my invention, what I claim as new and desire to protect by Letters Patent is:

1. In a gas main stopper, a frame structure comprising oppositely disposed shackles, means extending from each of said shackles and adapted to be telescopically arranged with respect to each other, spring means pivotally connected at their ends to said shackles and being normally biased to cause said frame to assume an approximately oval shape, a coating of flexible material surrounding said spring means and having its outer surface recessed to form a concaved seat, pneumatic means arranged in said seat and completely circumscribing said frame structure and having one end portion extending through one of said shackles and the means extending therefrom to a point exteriorly of said stopper, and an elastic diaphragm carried by said frame structure and including portions extended over said pneumatic means to be urged by the latter, upon inflation, into sealing engagement with the inner surface of a pipe.

2. In a gas main stopper, an expandible frame comprising oppositely disposed shackles, means extending from each of said shackles and adapted to be telescopically arranged with respect to each other, spring means pivotally connected at their ends to said shackles, said expandible frame being normally biased into approximately oval shape, a coating of flexible material surrounding said spring means and having its outer surface recessed to form a concaved seat, pneumatic means arranged in said seat and completely circumscribing said spring means and said shackles and having one end portion extending through one of said shackles and the means extending therefrom, to a point exteriorly of said stopper,

and an elastic diaphragm carried by said expandible frame and including portions extended over said pneumatic means to be urged by the latter, upon inflation, into sealing engagement with the inner surface of a pipe, said diaphragm being adapted to withstand internal pressure in said pipe, said coating of flexible material reinforcing said spring means against the torque created by said pressure.

3. In a gas main stopper including a frame structure comprising oppositely disposed shackles joined for movement toward and away from each other by a telescopic strut and spring means pivotally connected at their ends to said shackles to normally bias the frame into an oval shape together with pneumatic means arranged about said oval shaped frame and an elastic diaphragm carried on said frame for closing off a gas main, the provision of an anti-torque foundation for said frame and comprising, in combination, a coating of flexible material molded upon said spring means, a seat formation in the outer surface of said coating and adapted to receive said pneumatic means and to maintain the latter in alignment with said spring means.

4. In a gas main stopper including a frame structure comprising oppositely disposed shackles joined for movement toward and away from each other by a telescopic strut and spring means pivotally connected at their ends to said shackles to normally bias the frame into an oval shape together with pneumatic means arranged about said oval shaped frame and an elastic diaphragm carried on said frame for closing off gas mains, the provision of an anti-torque foundation for said frame adapted to prevent lateral movement of said stopper when the frame is set in stopping relation with respect to a gas main, said anti-torque foundation comprising bond elements surrounding said spring means at intervals and having a portion thereof affixed to the latter and portions thereof extending toward the outer periphery of said frame, a coating of flexible material molded upon said spring means and bond elements and having a concaved trough formed in the outside face thereof to provide a seat for said pneumatic means, said bond element reinforcing said concaved trough and transmitting torque exerted thereon to said spring means.

VICTOR E. ANKARLO.
